UNITED STATES PATENT OFFICE.

JAMES M. TERRY AND JOHN E. WHITE, OF ANADARKO, OKLAHOMA TERRITORY.

WINDOW-SHADE-HANGING DEVICE.

No. 863,468.

Specification of Letters Patent.

Patented Aug. 13, 1907.

Application filed September 21, 1906. Serial No. 335,627.

To all whom it may concern:

Be it known that we, JAMES M. TERRY and JOHN E. WHITE, citizens of the United States, residing at Anadarko, in the county of Caddo and Territory of Oklahoma, have invented new and useful Improvements in Window-Shade-Hanging Devices, of which the following is a specification.

This invention relates to window shade hanging devices, the object of the invention being to provide a simple and durable article of such character which can be readily and quickly applied and which can be easily adapted to windows of different sizes.

The device may be used in a variety of ways, but preferably is of such character as to particularly adapt it for direct attachment to a window sash.

In the drawings accompanying and forming a part of this specification we illustrate in detail one form of embodiment of the invention which to enable those skilled in the art to practice the same will be fully set forth in the following description, while the novelty of the invention will be included in the claims succeeding said description.

Referring to said drawings, Figure 1 is a perspective view of a window shade hanging device involving our invention. Fig. 2 is a like view of one of the brackets thereof and Fig. 3 is a similar view of the window shade carrier or supporting bracket.

Like characters refer to like parts throughout the several views.

Our device includes in its make-up two attaching brackets and a window shade carrier or supporting bracket. The attaching brackets are each denoted in a general way by 2, while the window shade carrier or supporting bracket is designated in a general way by 3.

We will describe in detail one of the attaching brackets, such description applying to the other, as they are in the present case of duplicate construction.

Referring now to Fig. 2, the bracket therein represented comprises a body member or main portion as 4 which may be like its companion member 5 of any desirable material or construction. The two parts ordinarily, however, consists of metal plates. These two bracket members 4 and 5 are related in such a way as to provide for longitudinal adjustment of said bracket 2, and one advantageous way of securing this result and which is shown in the drawings will be hereinafter set forth. The body member 4 is the one which in the present case is attached to the window, and for this purpose said body member 4 may have at its inner end or that end thereof next the window sash a lateral flange as 6 to fit flatwise against the sash and to be held thereto in some suitable way, as by nails, screws or other fastenings passed through perforations in said flange. The bracket member 5 is slidably supported by the bracket member 4 and this result we may secure by

forming in the said bracket member 4 several pairs of vertical slits each designated by 7 and the formation of which produces cross bars or loops as 8. The shank of the slidable bracket member 5 extends through these pairs of slits 7 and the cross bars 8 overlie said shank, by virtue of which the bracket member 5 can be freely moved longitudinally of the companion member to provide for the necessary adjustment of the bracket and the cross bars will be sufficiently resilient to frictionally hold the bracket member 5 in an adjusted position. This holding in an adjusted position may be also aided by the inherent resiliency of the two brackets, particularly if they be made of some thin sheet metal. At its extreme outer end the slidable bracket member 5 is provided with an upwardly extending arm 9 in the upper edge of which we form a downwardly extending slot 10 which slot with a duplicate slot on the other bracket member is adapted to receive the carrier or shade supporting bracket 3. This presents a very easy way of mounting or dismounting said carrier 3.

The carrier 3 consists of two sections as 11 and 12 preferably of sheet metal and each is provided at its outer end with a lateral flange as 13 having an opening 80 to receive one of the projecting studs or arbors of a curtain roller, the openings in the flanges 13 being of the familiar shape common in curtain roller brackets, that is, one being circular and the other rectangular. It will be understood that the carrier 3 between the flanges 13 at the opposite ends thereof fits in the slots 10 of the two brackets 2 when the parts are assembled. The section 11 of the shade carrier may as illustrated be provided with several pairs of vertical slits as 14 through which the narrow part of the section 12 slides, 90 the cross bars or loops 15, which are produced by the formation of said vertical slits 14, overlying the narrow portion of the said member 12. By reason of the relation between the two members 11 and 12 they may be extended or shortened to adapt the carrier 3 to the particular desired adjustment and when the adjustment is obtained it may be retained by the resilience of the two members forming said carrier or bracket 3 or simply by the resilience of the cross bars 15, so that as in the case of the two brackets 2 no independent holding means are necessary to preserve the adjusted relations.

It will be evident that the device is durable in that it has no parts that are subjected to undue wear, or which are liable to get out of order; it is simple in construction, by reason of which it can be applied or removed by unskilled persons. It is adjustable to meet various depths of window casings or frames, and various length curtains or shades and is very inexpensive to make. The construction is such that if desired the shade or curtain may extend into a room or compartment beyond the window casing or frame and

when the sash which carries the device is up the said curtain may be above the upper cross bar of said frame.

By using the device we may secure perfect ventilation without draft, through the upper half or another 5 part of a window. We also secure privacy in a room by drawing the shade over the lower sash while light and ventilation can be obtained through the upper part of window.

What we claim is:

- 10 1. In a device of the class described, a plurality of attaching brackets and a shade carrier sustained by said brackets, each of said brackets consisting of two parts one slotted to form loops for receiving the other for longitudinal adjustment of said brackets and the carrier comprising two members one having slits to form loops for receiving the other to provide for longitudinal adjustment of said carrier.
- 15 2. In a device of the class described, a curtain shade supporting bracket comprising two members, one slotted to form loops for receiving the other to provide for the longitudinal adjustment of said bracket combined with two attaching brackets, each of the latter being composed of an inner section having vertical slits arranged in pairs to thereby form loops, and an outer section to work through
- 20

said latter loops and thereby provide for the longitudinal adjustment of said attaching brackets, and the outer sections of the latter having open ended slots to receive said supporting bracket and the latter having at its opposite ends, portions which project outward beyond the attaching brackets to constitute bearings for a curtain shade 25 support.

3. The combination of attaching brackets, each consisting of a main member and an auxiliary member, one having a plurality of pairs of vertically disposed slits forming loops to receive for sliding movement the other member 30 and thereby provide for the longitudinal adjustment of said attaching brackets, said outer members having open slots, and a curtain shade supporting bracket to fit said slots and comprising two members, one having several pairs of vertical slits to form loops for slidably receiving 35 the other to provide for the longitudinal adjustment of said curtain shade supporting bracket.

In testimony whereof we have hereunto set our hands in presence of two subscribing witnesses.

JAMES M. TERRY.
JOHN E. WHITTE.
